HIS ATTORNEY

UNITED STATES PATENT OFFICE.

BURNHAM C. STICKNEY, OF ELIZABETH, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

No. 908,622.

Specification of Letters Patent.

Patented Jan. 5, 1909.

Application filed May 18, 1903. Serial No. 257,613.

To all whom it may concern:

Be it known that I, BURNHAM C. STICKNEY, a citizen of the United States, and resident of Elizabeth, in the county of Union and State of New Jersey, have invented certain new and useful Improvements in Type-Writing Machines, of which the following is a specification.

This invention relates to the paper guiding devices of typewriting machines, and particularly to the devices which guide the paper after it leaves the printing point, such for instance as illustrated in my U. S. Patent No. 658,931, dated October 2nd, 1900; and its object is to guide the leading edge of the paper away from the platen at the proper time, so as to avoid liability of the paper fouling with certain parts of the paper-guiding and other carriage mechanism.

My invention consists in certain combinations of devices and features of construction, as will be hereinafter set forth and particularly pointed out in the concluding claims.

In the drawings forming part of this specification, Figure 1 is a perspective view of a front adjustable paper guide of the class described in said patent. Fig. 2 is a cross section of a paper carriage of a "front strike" writing machine, showing my improvements applied thereto. Fig. 3 is a perspective view of a stripper for guiding the paper away from the platen. Fig. 4 is a front view of the paper carriage.

In the several views, like signs denote like parts.

The paper carriage comprises side bars 1 and 2, joined by a rear bar 3, which runs upon suitably supported balls 4. A platen 5 is mounted upon an axle 6 which is journaled in said side bars. Behind the platen is mounted a paper shelf 7, from which the paper is fed and guided around the platen by pressure rollers 8 and 9 and a deflector 10. A scale 11 at the front side of the platen is supported at its ends upon arms 12. These are pivoted upon the forward ends of fixed arms 13, which extend forwardly beneath the platen and have springs 14 for pressing the scale against the platen. Extending longitudinally of the platen and mounted thereover and in rear of a vertical plane passing through the platen

axis, is a bar 15, secured at its ends by screws 16 in the side bars 1 and 2 of the carriage. The bar is longitudinally grooved 55 at 15^a, and sleeves 17 are splined thereto so as to be independently adjustable therewith. From the outer end of each sleeve an arm 18 extends forwardly directly over the platen upon its delivery side; and at its 60 forward end the arm is bent inwardly longitudinally of the platen at 19; and upon this free end is laterally mounted a flexible finger 20, which is curved to suit the platen and extends forwardly and downwardly in 65 front thereof, at its lower end overlapping the platen scale, and at its upper end approximating the bar 15, and flaring upwardly so as to make a passage for the paper over the bar. The latter is provided 70 with a spring 21 for pressing the paper fingers against the platen or the paper thereon.

Between flanges 22 formed upon each sleeve 17, I mount a stripper 23, which may 75 be formed of sheet metal, and consists of a cylindrical body portion 24 formed loosely around the sleeve 17 so as to pivot thereon, and a forwardly and downwardly inclined stripper portion 25, whose forward end may 80 rest slightly upon the platen, the weight of the stripper being preferably sufficient to keep it in contact with the platen. The stripper which is confined against endwise displacement by the flanges, extends be- 85 tween the bar 15 and the platen, and is ad- jacent to the upper end of the paper guiding finger 20, the latter overlying the former, as seen at Fig. 2, and the stripper and finger coöperate with opposite sides of the paper 90 to give positive direction to the movement of the paper. The strippers also extend inwardly from said fingers towards each other, as at Fig. 4.

The stripper preferably widens from its 95 front portion to its rear portion, the edge connecting said portions being oblique, as at 26, thereby assisting in stripping the paper from the platen.

In operation, the paper is fed in by the 100 rollers 8 and 9 and guided by the deflector 10 and the platen scale 11, from which it feeds between the fingers 20 and the platen and passes onward over the bar 15, emerg-

ing between the arms 18 and through the passage formed by the coöperation of the fingers 20 and strippers 23.

Variations may be resorted to within the 5 scope of my invention.

What I claim as new and desire to secure by Letters Patent, is:—

1. In a typewriting machine, the combination with a platen, of paper guiding 10 means adjustable along the platen, and a gravity-operated stripper connected to said paper guiding means.

2. In a typewriting machine, the combination with a platen, and a bar extending 15 along the platen, a paper-guiding device mounted upon said bar for adjustment therewith, and a stripper pivoted upon said paper-guiding device.

3. In a typewriting machine, the combination with a platen, of a bar extending 20 along the platen, a paper-guiding device supported upon said bar for adjustment therewith, said paper-guiding device extending forwardly from said bar directly 25 over the platen and including a finger which extends partly around the platen, and said bar being arranged relatively to the platen and the guide so that the paper may feed between said finger and the platen and pass 30 onward over the bar, and means adjustable with said paper-guiding device for stripping the paper from the platen.

4. In a typewriting machine, the combination with a platen, of a bar parallel therewith and arranged above the platen, a device 35 adjustably mounted upon said bar and extending forwardly therefrom directly over the platen for guiding the paper rearwardly over said bar when it has passed the printing point, and a gravity-operated stripper connected to said paper-guiding device so as to be adjustable therewith.

5. In a front strike typewriting machine, the combination with a platen of a paper 45 guide curved to suit the platen and terminating at its lower end in front of the platen and extending upwardly and rearwardly over the platen, a bar parallel with the platen and arranged at the rear end 50 of said guide, means extending rearwardly over the platen for supporting said guide adjustably upon said bar, said supporting means being so arranged that the paper may pass under the guide and over the bar, and 55 a pivoted stripper between the bar and the platen.

6. In a typewriting machine, the combination of a platen, a bar extending along the platen, a pair of arms adjustable along said 60 bar and extending therefrom in a direction opposite to that of the advance movement of the paper, offset guiding fingers carried by said arms, and a pair of strippers; the construction and arrangement of the parts being such that the paper is fed between said 65

arms and under the guiding fingers and over the strippers and the bar.

7. In a typewriting machine, the combination with a platen, of fingers for guiding the paper at the delivery side of the platen and 70 after it passes the printing point, and adjacent strippers, the fingers being adapted to coöperate with one side of the paper and the strippers with the other side thereof, a paper table, and a bar forward of the paper table 75 and along which said fingers and strippers are adjustable; said strippers operating to direct the paper over the bar.

8. In a typewriting machine, the combination with a platen, of a bar parallel therewith, an arm having means for engaging said bar so as to be capable of adjustment therewith, a stripper attached to said engaging means, and a paper guide supported laterally upon the free end of said arm; the 80 relation of the parts being such that the paper when issuing from the machine passes over said stripper and said bar and by said arm.

9. In a front strike typewriting machine, 90 the combination with a platen, of a bar above and parallel therewith, a sleeve adjustable along said bar, an arm extending forwardly from said sleeve, a downwardly extending paper guide attached laterally upon the forward end of said arm and so as to direct the paper upwardly and rearwardly from the printing point, and a stripper also mounted upon said sleeve and extending forwardly therefrom to direct the 100 paper over the bar.

10. In a typewriting machine, the combination with a platen, of a bar parallel therewith, a sleeve adjustable along said bar, an arm extending forwardly from said 105 sleeve, a paper guide attached laterally to the forward end of said arm, and a stripper also mounted upon said sleeve and extending forwardly therefrom; said sleeve being splined to said rod, said arm being fixed to 110 the sleeve, and said sleeve having flanges between which said stripper is confined.

11. In a typewriting machine, the combination with a platen, of a bar parallel therewith, a sleeve adjustable along said bar, 115 an arm extending forwardly from said sleeve, a paper guide attached laterally upon the forward end of said arm, and a stripper also mounted upon said sleeve and extending forwardly therefrom; said stripper consisting of a thin metal plate formed around the sleeve and inclining forwardly and downwardly therefrom, and said sleeve having means for preventing displacement of the stripper.

12. In a front strike writing machine, the combination with a platen and a bar mounted thereover, of a pair of arms adjustable along the bar and having paper-guiding 120 fingers which conduct the paper upwardly 130

and rearwardly from the printing point, said fingers being between said arms, and strippers coöperating with said guiding fingers and adjustable therewith along the bar; said fingers extending over said strippers so that the paper is directed over said bar.

13. In a front strike writing machine, the combination with a platen and a bar mounted thereover; of a pair of arms adjustable along the bar and having paper guiding fingers which conduct the paper upwardly and rearwardly from the printing point, said fingers being between said arms, and strippers coöperating with said guiding fingers and adjustable therewith along the bar; said fingers extending over said strippers, and the latter extending inwardly from said fingers so as to direct the paper over said bar.

14. In a typewriting machine, the combination with a platen, of a bar parallel therewith, a sleeve adjustable along said bar, an arm extending forwardly from said sleeve, a paper guide attached to the forward end of said arm, and a stripper also mounted upon said sleeve and extending forwardly therefrom; said stripper inclining forwardly and downwardly from said sleeve, and widening from its front portion to its rear portion.

Signed at the borough of Manhattan, city of New York, in the county of New York, and State of New York, this 15th day of May A. D. 1903.
